US0D1052582S

(12) **United States Design Patent** (10) Patent No.: **US D1,052,582 S**
He et al. (45) Date of Patent: ** Nov. 26, 2024

(54) **SMARTWATCH**

(71) Applicant: **Creek Wearable Technology Co., Ltd.**,
Shenzhen (CN)

(72) Inventors: **An He**, Shenzhen (CN); **Kexin Tong**,
Shenzhen (CN)

(73) Assignee: **Creek Wearable Technology Co Ltd**,
Shenzhen (CN)

(**) Term: **15 Years**

(21) Appl. No.: **35/517,988**

(22) Filed: **Mar. 30, 2023**

(80) **Hague Agreement Data**

Int. Filing Date: **Mar. 30, 2023**

Int. Reg. No.: **DM/230472**

Int. Reg. Date: **Mar. 30, 2023**

Int. Reg. Pub. Date: **Aug. 4, 2023**

(30) **Foreign Application Priority Data**

Feb. 27, 2023 (CN) 202330078280.8

(51) **LOC (14) Cl.** **14-02**

(52) **U.S. Cl.**
